Patented Aug. 11, 1914.

UNITED STATES PATENT OFFICE.

WILLIAM E. BURCKY, OF CHICAGO, ILLINOIS.

LAMP.

1,106,776.

Specification of Letters Patent. Patented Aug. 11, 1914.

Application filed April 1, 1914. Serial No. 828,787.

To all whom it may concern:

Be it known that I, WILLIAM E. BURCKY, a citizen of the United States, residing at Chicago, in the county of Cook and State of Illinois, have invented a new and useful Improvement in Lamps, of which the following is a specification.

My invention relates to an improvement in the glass face for lamps of the kind used as signals on vehicles; and it relates particularly to an improvement in the lamp-face of Letters Patent of the United States No. 1,091,118, granted to me March 24, 1914.

In the accompanying drawing, Figure 1 is a broken view of a lamp-body provided with my improved face shown in vertical section; Fig. 2 shows the face in front elevation, and Fig. 3 is a sectional view of a portion of the face, showing a modification.

The glass lamp-face 4, shown in circular form though it may be provided in any desired shape, fits the hinged annular head 5 on a lamp 6, which may be an automobile-lamp of any suitable construction. The primary improvement in the present construction lies in forming the ridge-faced device of transparent glass hollow on its rear side, the hollow side being of the same, or approximately the same angular shape in cross-section as the outer side. This construction facilitates the manufacture by enabling the lamp-face to be formed of a uniform thickness of the glass throughout (except that the edge 4^a should be relatively thicker, as represented, for strength), as by molding it between correspondingly-shaped female and male members of a mold. Moreover, and particularly, the downwardly-inclined surface of each ridge being rendered translucent as by darkening or coating it with a translucent paint, shellac or varnish, as shown at 7, the hollow construction of the ridge enables the coating to be applied to the inner surface of that part of the ridge, where it is more durable than when applied to the outer surface, being protected from the weather and shielded against abrasion and wear. Light from the lamp 6 passing through the translucent surfaces 7 is so modified in intensity as to exhibit the face 4 with a mild degree of illumination, while these surfaces reflect rays through the lower, transparent, surfaces 8 upon the ground to brilliantly illuminate the latter, thereby

throwing the light-signal without the blind-

ing effect of light-rays passed horizontally through a transparent-glass face, which is liable to cause accidents in automobiling. It is found desirable to incline downwardly the transparent surfaces 8 slightly in the backward direction, as represented, to cause the light-rays refracted through them to be thrown farther forward than when these surfaces are horizontal. Then, it is also advantageous to corrugate these transparent surfaces, or ridge-sections, as shown at 8^a in Fig. 3, thereby to increase the extent and number of surfaces through which the light from the translucent surfaces, or ridge-sections, is thrown upon the ground, thus to augment the lighting effect thereon. As in the device of my said patent, it is the intention to provide my present invention in, and to include therein, any form of the device for covering or shielding the light-rays passing through the face of a lamp-body.

What I claim as new and desire to secure by Letters Patent is:—

1. In a glass lamp-face, a hollow ridge extending transversely across the face and having its inner and outer faces parallel with each other, said ridge having a translucent upper side inclined downwardly and forwardly.

2. In a glass lamp-face, a hollow angular ridge extending transversely across the face and having its inner and outer faces parallel with each other, said ridge having its upper side formed of translucent glass and inclined downwardly and forwardly and its lower side formed of transparent glass.

3. A glass lamp-face comprising a series of angular ridges of substantial V-shape in cross section, extending transversely across the face and having their inner and outer faces parallel with each other, said ridges having downwardly and forwardly inclined translucent upper sides and lower transparent sides.

4. A glass lamp-face comprising a series of hollow ridges of substantially the same angular cross-section on both sides, each ridge being formed of a translucent downwardly-inclined upper side and a corrugated transparent lower side.

WILLIAM E. BURCKY.
